US0D1014348S

(12) **United States Design Patent** (10) **Patent No.:** **US D1,014,348 S**
(45) **Date of Patent:** **** Feb. 13, 2024**

(54) **VEHICLE VALANCE**

(71) Applicant: **Dr. Ing. h.c. F. Porsche**
Aktiengesellschaft, Stuttgart (DE)

(72) Inventor: **Emiel Burki**, Stuttgart (DE)

(73) Assignee: **Dr. Ing. h.c. F. Porsche**
Aktiengesellschaft

(**) Term: **15 Years**

(21) Appl. No.: **29/803,720**

(22) Filed: **Aug. 16, 2021**

(30) **Foreign Application Priority Data**

Feb. 17, 2021 (EM) 8436406-0010
